UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

FIREARM.

1,146,502.

Specification of Letters Patent. Patented July 13, 1915.

Application filed August 17, 1914. Serial No. 857,158.

To all whom it may concern:

Be it known that I, THOMAS C. JOHNSON, a citizen of the United States, residing at New Haven, in the county of New Haven 5 and State of Connecticut, have invented a new and useful Improvement in Firearms; and I do hereby declare the following, when taken in connection with the accompanying drawings and the characters of reference 10 marked thereon, to be a full, clear, and exact description of the same, and which said drawings constitute part of this application, and represent, in—

Figure 1, a broken view in side elevation 15 of a gun having its receiver provided at its forward end with a depending abutment-lug constructed in accordance with my invention. Fig. 2, a broken detached view of the forward end of the receiver, showing 20 my improved depending abutment-lug. Fig. 3, a view in vertical section on the line A—B of Fig. 2, looking forward toward the rear face of the abutment-lug. Fig. 4, a detached view of the receiver in front elevation. Fig. 5, a view in rear elevation of the 25 forearm. Fig. 6, a view in front elevation of the butt-stock.

My invention relates to an improvement 30 in that class of small arms in which the stock of the arm is divided into a butt-stock and a forearm, the object being to prevent these parts from being splintered during the heavy shocks of recoil, especially in bolt guns.

With these ends in view, my invention 35 consists in a gun having its receiver provided at its forward end with a depending abutment-lug, the forward and rear faces of which are respectively adapted to support 40 the rear end of the forearm and the forward end of the butt-stock.

My invention further consists in certain 45 details of construction and combination of parts as will be hereinafter pointed out and described in the claims.

In carrying out my invention as herein shown, I form a heavy depending recoil-taking abutment-lug 2 upon the forward end 50 of the receiver 3, which may be of any approved construction. By preference, the said lug 2 is made integral with the forward end of the receiver 3, though that is not imperative. The forward face of the lug 2 is formed, as shown, with a large, shallow recess 4 for the reception of a corresponding

tenon 5 formed upon the rear end of the forestock 6, the front end of which is firmly fastened to the barrel 7 in any one of a variety of ways, well understood. The barrel 7 is screwed in the usual manner into the receiver 3, the entrance of the tenon 5 into the shallow recess 4 preventing the barrel 7 from unscrewing in case for any reason it works loose. As shown, the rear face of the lug 2 is formed with three shallow cuts or 60 recesses 8, 9 and 10 forming sockets for the reception of corresponding tenons 11, 12 and 13 formed upon the forward end of the butt-stock 14, the rear end of which is supported in any convenient manner. 70

Inasmuch as the lug 2 is a relatively heavy part and formed directly upon the receiver, it is able to withstand the heavy shocks of recoil resulting from the firing of large cartridges in the gun. As shown, 75 the front and rear surfaces of this lug 2 are left with large, flat areas for the abutment of the forearm and butt-stock. Thus, the bottom 15 of the recess 4 constitutes a large area to receive the impact of the flat 80 face of the tenon 5 at the time of recoil, while the flat rear face 16 of the lug 2 forms a large, flat surface for impingement upon the flat forward end of the butt-stock 14 at the time of recoil. The particular formation of the front and rear faces of the abutment-lug 2 to adapt it to receive and support and take the thrusts of recoil of the 85 forearm and butt-stock may be considerably varied, and I do not limit myself to the exact construction shown. I call particular attention to the fact that in its external contour the lug 2 conforms to the contours of the forearm 6 and butt-stock 14 so as to unite them in a continuous line and form, 90 in a sense, a continuation of both. 95

I claim:

1. A fire arm having its receiver provided at its forward end with a depending abutment-lug the forward and rear faces of which are adapted to receive and support the adjacent ends of the forearm and butt-stock of the firearm, the said ends being separated by a large, flat recoil-taking surface forming an integral part of the said 100 lug.

2. A fire arm having its receiver provided at its forward end with a depending, integral abutment-lug the forward and rear faces of which are recessed to receive and 110

support the adjacent ends of the forearm and butt-stock of the firearm, the said ends being separated by a large, flat recoil-taking surface forming the bottom of each recess and constituting an integral part of the said lug.

3. A fire arm having its receiver provided at its forward end with a depending abutment-lug the forward and rear faces of which are recessed to receive and support the adjacent ends of the forearm and butt-stock of the gun to which the external contour of the said lug conforms so as to virtually form a continuation of each, the said ends being separated by a large flat recoil-taking surface forming the bottom of each recess and constituting an integral part of the said lug.

4. In a fire arm, the combination with a receiver provided at its forward end with a depending abutment-lug having its forward face furnished with a large shallow

recess having a flat bottom and its rear face formed with one or more cuts or recesses, of a forearm provided at its rear end with a tenon adapted to fit into the said recess in the forward face of the said lug, and a butt-stock adapted at its forward end to fit into the cut or cuts in the rear face of the said lug the exterior lines of which conform to the lines of the adjacent ends of the forearm and butt-stock so that it constitutes a virtual continuation of the said parts, the adjacent ends of the said forestock and forearm being separated by a large flat recoil-taking surface constituting an integral part of the said lug.

In testimony whereof, I have signed this specification in the presence of two subscribing witnesses.

THOMAS C. JOHNSON.
